MEANS FOR CENTERING AND CLAMPING A
FLASK IN POSITION IN CENTRIFUGAL
CASTING MACHINESJohn D. Guelph, Paterson, N. J., assignor to
A. R. D. Corporation, New York, N. Y., a corpora-
tion of New York

Application May 24, 1947, Serial No. 750,204

2 Claims. (Cl. 22—65)

1

This invention relates to centrifugal casting machines. More particularly, it relates to means for centering and clamping a flask in position on the rotating table of a centrifugal casting machine.

An object of this invention is to provide a new and improved centrifugal casting machine.

Another object of this invention is to provide a centrifugal casting machine with means for easily, quickly and automatically centering the flask on the table and clamping it in position.

An additional object of this invention is to provide a centrifugal casting machine having centering and clamping means automatically adaptable to different flask diameters.

A further object of this invention is to provide a centrifugal casting machine wherein the centrifugal force developed in the elements of the flask-clamping means rigidly clamps and holds the flask during the casting operation.

Other and additional objects of the invention will become apparent hereinafter.

The objects of the invention are obtained, in general, by mounting a plurality of spaced flask-clamping jaws arranged equidistantly from the center axis of the machine for movement in a radial path to and from the center axis of the machine and providing means for simultaneously moving said jaws in the desired direction in said radial paths whereby a flask disposed therebetween is centered and gripped or released depending on the direction of movement of the jaws. Means are also provided to utilize the centrifugal force developed during rotation of the machine during the casting operation to securely clamp and hold the flask in position.

In one embodiment of the invention, each jaw is carried on a separate jaw holder, and each jaw holder is slidably mounted on a separate screw shaft which, upon rotation, will cause the jaw holder thereon to move in a radial path to and from the center axis of the machine depending on the direction of rotation of the screw shaft. Each screw shaft is provided at its inner end with a bevel gear which, in turn, is in meshing relationship with a main bevel gear. Means are provided to rotate the main bevel gear in the desired direction whereby the jaws will be moved simultaneously inwardly toward or outwardly from the center axis of the machine. The means for rotating the main gear is provided with means which utilize the centrifugal force developed during rotation of the machine so as to transmit the torque so developed to the main gear where-

2

by the jaws will exert a clamping effect on the flask disposed therebetween during the casting operation.

The nature of the invention will become more apparent when considered in connection with the accompanying drawings forming a part of this specification, and wherein:

Figure 1 is a vertical section of a machine embodying the principles of this invention;

Figure 2 is a section taken on the line 2—2 of Figure 1; and

Figure 3 is a section taken on the line 3—3 of Figure 1.

Referring now to the drawings, wherein like reference numerals designate like parts, the reference numeral 10 designates a turn-table which is secured in any convenient manner, as by screws 12, to a flange 14 of a rotatable spindle 16. The spindle 16 is rotated about its center axis in any well-known manner, and since the details of construction of the spindle and the drive therefor form no part of this invention, further description thereof is deemed unnecessary.

25 A plate 18 disposed in opposed grooves in the flange 14 and the under surface of the turn-table 10 aids in transmitting the torque of the spindle 16 to the table 10. A flask 20 containing the mold and into which the molten metal is to be ladled is adapted to be positioned on a flask 20 rest pad 22 on a jaw-supporting table 24 which is secured rigidly on spaced brackets 26 which, in turn, are secured rigidly to the table 10.

In the embodiment of the invention illustrated in the drawings, the flask 20 is adapted to be centered and gripped between or released from three jaw plates 30 arranged in spaced relationship to each other and equidistantly from the center axis of the machine. Since all of the jaw plates 30 are identically mounted and operated, 35 the details of the mounting and operation of only one of such jaw plates will be described.

Each jaw plate 30 is secured to a jaw holder 32 in any convenient manner, as by screws 34, and each jaw holder 32 is provided with a threaded 40 hole through which a screw shaft 36 extends. Each jaw holder 32 is provided with extensions 40 which are adapted to slide in a slot 42 in the jaw-supporting table 24. Each slot 42, as shown in Figure 2, extends in a radial direction relative to the center axis of the machine.

45 Each screw shaft 36 is rotatably mounted in bushings 44 and 46. The bushing 44 is secured in a support 48 depending from the jaw table 24 and the bushing 46 is carried in a support 50 secured to the table 10 in any convenient manner.

A cap 54 is pinned to the outer end of each screw shaft 36, and on its inner end each screw shaft 36 is provided with a bevel gear 56 in mesh with a main bevel gear 58 rotatably mounted on a post 60. The center axis of the post 60 is located in the center axis of the machine and is secured at the bottom thereof to the turn-table 10 and at the top thereof to the jaw-supporting table 24. A radial bearing 62 and a thrust bearing 64 are provided between the main bevel gear 58 and the post 60.

From the foregoing description, it is apparent that upon the rotation of the main gear 58 each of the screw shaft gears 56 will be rotated in the same direction, with the result that each of the jaw holders 32 on the respective screw shafts 36 will be moved simultaneously, depending upon the direction of rotation of the main gear 58, toward or away from the center axis of the machine.

Means are provided to rotate the main gear 58 whereby the jaw holders 32 can be moved simultaneously in the desired direction. In the form shown, main gear 58 is in mesh with and rotated by a bevel gear 66 secured to the inner end of a shaft 68 rotatably mounted in bushings 70 in the brackets 26. At its outer end, the shaft 68 is provided with a gear 72 which is in mesh with a bevel gear 74 secured to a shaft 76 rotatably mounted in a bushing 78 carried by the jaw-supporting table 24. A ratchet 80 is appropriately secured to the shaft 76 and a locking weight member 82 is journaled on the ratchet 80. The locking weight member 82 is provided with a hole through which the shaft 76 extends and also with a bore in which a plunger 84 is disposed. It is to be noted that the locking weight member is eccentrically mounted on the shaft 76. The plunger 84 is provided with a tooth 86 which is adapted to engage one of the grooves 88 of the ratchet 80. The plunger 84 is continuously urged into locking position with the ratchet 80 by a compression spring 90. On its outer end, the plunger is provided with a knurled knob 92. A pin 94 secured to the knob 92 extends into a hole in the member 82 when the plunger is in locking position.

A lever 96 keyed to the outer end of the shaft 76 is provided with manual grip portions 98. It is manifest that when the tooth 86 of the plunger 84 is in engagement with a groove 88 in the ratchet member 80 upon rotation of the shaft 76 through the lever 96 the locking weight member 82 will rotate therewith. When the plunger 84 is retracted by manually engaging the knob 92 and moving it outwardly to the right in Figure 3, the tooth 86 will be withdrawn from the groove and the locking weight member 82 can be rotated about the shaft 76 and the ratchet member 80. The reason for this will become apparent hereinafter.

Each of the jaw holders 32 has secured thereto a jaw front cover 102 and a jaw back cover 104 which are adapted to cover or close the slots in the jaw-supporting table 24. It is to be noted that the jaw front covers 102 are disposed beneath the flask rest pad 22 and the vertical legs thereof are positioned in grooves 103 whereby screws 106 which fasten them to the jaw will not be in engagement with the flask 20. A shield or housing 110 is secured to both the turn-table 10 and jaw-supporting table 24.

In operation, the flask 20 is disposed on the flask rest pad 22 and the operator grips the handle 92 and operates it so that the lever 96 is rotated in such a direction that the rotation of the gear 66 will impart rotation to the main bevel gear 58 in a direction so as to rotate the gears 56 on the

screw shafts 36 in a direction whereby the jaw holders 32 will be moved on their respective screw shafts in their radial path toward the center of the machine and until they center and grip the flask. At this point, the locking weight member 82 may be at any position relative to the table. The plunger 84 is now retracted and the locking weight member 82 rotated about the shaft 76 and the ratchet 80 until it assumes a position such as shown in dotted line position in Figure 2, and hereafter described. The plunger is then released so as to lock the locking member 82 to the ratchet 80.

The spindle 16 is then rotated at a definite speed, and the molten metal ladled into the upper end of the flask. After the metal has solidified, the table is brought to rest, the lever 96 is operated so as to move the jaws 30 into flask-releasing position, and the flask removed. The cycle of operations is repeated for each casting.

During the time interval that the table is rotating, a centrifugal force F is effective at the center of gravity of the locking weight 82, as at G. A moment FL is therefore effective to turn the locking member 82 and with it the ratchet 80 about center O. It is obvious that the torque so developed will be transmitted by the gearing above described so as to exert a clamping force by the jaws on the flask. When the rotation of the table has stopped, no torque will be transmitted to the jaws so that the clamping force is released, whereby the jaws can be easily moved as previously described.

Though the invention has been specifically described in connection with a turn-table rigidly secured to the spindle, the invention is not restricted thereto. The turn-table and its associated elements can be provided with an adapter and removably secured in position on the spindle as set forth in my copending application filed on even date herewith for "Centrifugal Casting Machines."

The invention provides a centrifugal casting machine which quickly centers the flask and clamps it in position and utilizes the centrifugal force developed during the operation of the machine to rigidly clamp and hold the flask in position during the clamping operation. The clamping force for positively holding the flask in position is therefore automatically applied and released by the rotary motion of the table. Consequently, the operator is relieved of the time and manual effort ordinarily required for this purpose and a higher production rate is achieved with less physical effort. Also, since the mechanism of this invention is automatically adaptable to different flask diameters, no time is consumed for the adjustment of either the positioning or clamping means, irrespective of the diameters of the flasks successively used in the machine, and a higher production rate is obtained. The higher production rate results in a considerably lower unit cost for the product.

Since it is obvious that various changes and modifications can be made in the above description without departing from the nature or spirit thereof, this invention is not restricted thereto except as set forth in the appended claims.

I claim:

1. In a centrifugal casting machine, a turn-table, means to rotate said turn-table, a jaw-supporting table secured to said turn-table, a plurality of spaced jaws arranged equidistantly from the center axis of the machine, each jaw being adapted to slide radially in said jaw-supporting

5

table relative to the center axis of said machine whereby a flask disposed between said jaws will be centered and gripped thereby or released therefrom, each jaw being movably mounted on a separate screw shaft, a gear on each screw shaft, a main gear meshing simultaneously with said screw shaft gears to actuate the jaws in unison, a drive shaft extending axially of said turn-table and positioned eccentrically thereof, means gearing said drive shaft to drive said screw shafts, a weight member rotatably mounted on said drive shaft and positioned eccentrically thereon so that during rotation of said turn-table a centrifugal force will be developed thereby, and a releasable connection connecting said weight member to said drive shaft whereby said weight member can be positioned on said jaws to exert centrifugal force for holding a clamping pressure.

2. In a centrifugal casting machine, a turn-table, means to rotate said turn-table, a jaw-supporting table secured to said turn-table, a plurality of spaced jaws arranged equidistantly from the center axis of the machine, each jaw being adapted to slide radially in said jaw-supporting table relative to the center axis of said machine whereby a flask disposed between said jaws will be centered and gripped thereby or released therefrom, each jaw being movably mounted on a separate screw shaft, a gear on each screw shaft, a main gear meshing simultaneously with said screw shaft gears to actuate the jaws in uni-
